UNITED STATES PATENT OFFICE.

ABRAHAM VAN ROEKEL, OF ORANGE CITY, IOWA.

CORN-DRYING RACK.

1,069,913.

Specification of Letters Patent. Patented Aug. 12, 1913.

Application filed September 15, 1910. Serial No. 582,113.

To all whom it may concern:

Be it known that I, ABRAHAM VAN ROEKEL, a citizen of the United States, residing at Orange City, Sioux county, State 5 of Iowa, have invented a certain new and useful Corn-Drying Rack, of which the following is a specification.

The object of my invention is to provide a corn drying rack which is exceedingly 10 simple in construction and which is supported on legs so that the corn is beyond the reach of such destructive creatures as rats and mice.

In the accompanying drawings: Figure 1 15 is a side elevation of my improved corn drying rack, and Fig. 2 is an end view of the same.

The rectangular frame 10 is mounted on legs 11. The open sides of the frame are 20 covered with a lined lattice-work for holding the corn during the drying operation. This lattice-work consists of horizontal strips or wires 12 suitably spaced, and vertical strips or wires 13. The wires are suitably secured to the frame as by means of 25 staples 14. The points where the wires cross are preferably welded or woven as indicated at 15. The wires on opposite sides of the frame are substantially in alinement so that 30 the ears of corn may be properly supported by the wires. If the rack is of considerable length an intermediate partition 16 is em-

ployed, the horizontal wires being fastened to this partition. The supporting legs 11 may be readily stamped or bent out of sheet 35 metal, the end legs being of substantially inverted V-shaped form, while the center supporting leg is of substantially upright V-shaped form.

Having thus described my invention what 40 I claim as new and desire to secure by Letters Patent of the United States is:

In combination, a corn drying rack, an open frame, said frame comprising three upright members and cross pieces for forming the top and bottom of said frame, and means for securing said parts together, a lattice work of wire fastened over the open sides of said frame for supporting the ears 45 of corn, and means attached to said frame 50 for supporting the same above the ground, said means consisting of a pair of legs, each comprising a single strip of sheet metal bent to form two downwardly diverging extensions and fastened to the frame at the bend 55 of said strip, and a V-shaped leg secured to the bottom of said frame on the underside thereof, substantially as and for the purposes described.

ABRAHAM ^{his} VAN ROEKEL.
